(57) **CLAIM**

The ornamental design for a tack cloth, as shown and described.

DESCRIPTION

FIG. 1 is a perspective view of the tack cloth embodying my design;

FIG. 2 is a top plan view of the tack cloth seen in FIG. 1; FIG. 3 is a side view of the tack cloth seen in FIG. 2; and, FIG. 4 is an enlarged view of a portion of the tack cloth designated at 4 in FIG. 2.

The pattern fragmentarily shown in FIGS. 1 and 2 is understood to be uniformly repeated.
